UNITED STATES PATENT OFFICE.

SAMUEL V. WEEKS, OF HIGHLAND PARK, TENNESSEE, ASSIGNOR TO EMERSON MANUFACTURING COMPANY, OF ROCKFORD, ILLINOIS, A CORPORATION OF ILLINOIS.

PLOW.

No. 857,967.

Specification of Letters Patent.

Patented June 25, 1907.

Application filed November 11, 1905, Serial No. 286,851.

To all whom it may concern:

Be it known that I, SAMUEL V. WEEKS, a citizen of the United States, residing at Highland Park, in the county of Hamilton and State of Tennessee, have invented a new and useful Plow, of which the following is a specification.

This invention relates particularly to gang disk plows, though there are certain features that are not necessarily limited to this type, as will be apparent when the nature of the invention is understood.

Among the many objects of the invention, one of the most important is to provide a novel gang plow, wherein the different plowing devices or disks are permitted to move relatively to each other in such a manner that the plow, as a whole, may conform to the unevenness of the ground and will properly furrow the same without regard to the depressions or elevations.

Another object is to provide supporting means for the various plows, which will enable them to have the desired relative movement, and also to secure a structure that is much lighter in weight without regard to the size or number of plowing devices employed.

A further object is to provide novel draft mechanism in connection with a gang of plows, whereby each plow, though depending to a certain extent on a primary connection with the draft appliance, has also a draft connection of its own, said mechanism eliminating side draft and lateral strains on the various parts.

Still another object is to provide means which will hold the plows to their work, while making turns and the like, and will permit the relative adjustment of said devices to take more or less land.

An embodiment of the invention that is at present considered the preferable one is illustrated in the accompanying drawings and is described in the following specification. An inspection of the claims hereto appended will show, however, that said invention is not limited to the particular structure disclosed.

In the drawings: Figure 1 is a top plan view of the plow. Fig. 2 is a side elevation of the same. Fig. 3 is a detail perspective view of the draft appliance, the first beam and the parts associated therewith. Fig. 4 is a vertical sectional view through the carrier or mounting. Fig. 5 is a longitudinal sectional

view through one of the beams and the parts connected thereto. Fig. 6 is a plan view of one of the disk carriers. Fig. 7 is a side elevation of the same. Fig. 8 is a perspective view of the standard which carries the front furrow wheel. Fig. 9 is a detail sectional view on the line 9—9 of Fig. 1. Fig. 10 is a view of the front furrow wheel and associated parts taken from the side opposite to that shown in Fig. 3. Fig. 11 is a detail perspective view of one of the supporting wheel axles. Fig. 12 is a detail perspective view of one of the standards in which said axles are mounted.

Similar reference numerals designate corresponding parts in all the figures of the drawings.

In the embodiment illustrated, a draft appliance is employed, comprising a bar 9, located across the line of draft, having a rearwardly extending portion 10 pivoted thereto, the rear end of said rearwardly extending portion being provided with an offset arm 11. In the structure shown, the parts 10 and 11 are separate sections bolted together, as shown at 12, one end of the arm 11 being fitted between flanges 13, on the rear end of the rearwardly extending section 10, and said section 10 being pivoted, as shown at 14, to a rearwardly extending ear portion 14^a, rigidly affixed to the end of the draft bar 9, the swinging movement of said section 10 being limited by a lug 15^a, carried by the section 10 and engaging spaced abutments 16^a on the ear portion 14^a. Connected to the offset 11 is a chain of sections or beams 15, said chain extending diagonally across the line of draft and the beams thereof being located longitudinally of such line of draft. The particular means for connecting the various beams will, it is thought, be clear by reference to Figs. 3 and 4.

Each beam 15 is provided at its rear end with a tapered upright boxing 16, in which is journaled the spindle 17 of a disk carrier or mounting, comprising a body 18, having at its lower end an inclined tapered boxing 19, in which is journaled the spindle 20 of the plowing disk 21. The spindle 20 is held in place by the nut 22 and washer 23 of a bolt 24, passing through said spindle and through the disk, and the spindle 17 is secured in place by a cap piece 25, bolted, as shown at 26, or otherwise secured to the spindle 17. The body 18 of the carrier has an offset por-

tion 27, extending on the opposite side to the plowing disk and carrying a substantially horizontal pintle 28. The front end of the plow beam 15 next in rear is bifurcated and has spaced eyes 29, journaled on the pintle, the same being held in place by a link collar 30, that embraces the eyes 29, and is secured to the pintle by a set screw 31. The pintle 28 is of sufficient length to permit of the adjustment of the beam along the same, and thus the distance between the two beams connected can be varied considerably. From the above, it will be apparent that each beam is connected to the beam next adjacent by means of the disk carrier of said adjacent beam and that the rear beam is capable of a vertical swinging movement on the pintle while it is also permitted to have a substantially horizontal swinging movement, as the disk carrier is journaled on a substantially vertical axis.

The foremost beam 15 is connected to the offset 11 of the draft appliance by means of a pressure member 32, that is in the nature of a lever, the front end of said member having a guideway 33, that receives the offset portion 11, which is fastened to the member by a bolt 34. A series of openings, as 35, formed in the offset portion, permits the adjustment of the member along the same. The member 32 is fulcrumed between its ends by means of a pintle 36, to the front end of the foremost beam 15, while its rear end is in the form of a bill 37, that bears upon the beam in rear of the pivotal connection. On each of the pintles 28 is also mounted a pressure member 38, each member being journaled between its ends and being fitted between the beam eyes 29 that are thereupon. The rear ends of these various members are in the form of bills 39 that bear upon the beams, while their front ends are formed into eyes 40. Draft devices in the form of links 41 have their rear ends engaged in the eyes, while their front ends are connected to a common ring 42, connected by a stirrup 43, and bolt 44, to the main draft bar 9. The links may be either heavy and substantially rigid or they may be flexible. The stirrup 43 is adjustable along the draft bar and is adapted to be held in different adjusted positions, the bar 9 having a series of openings 45, to receive the bolt 44. A spreader bar 46 connects the front portions of the draft links 41 and serves to maintain the main portions thereof parallel to the line of draft and in alignment with their corresponding beams.

For the purpose of supporting the above described structure and gaging the depth at which the disks operate, the following mechanism is preferably employed. An outstanding arm 47, preferably forming an integral part of the ear element 14^a, terminates at its outer end in an upstanding guideway 49, and a forwardly extending ear 50. The

guideway 49 is slidable upon an upright standard 51, carrying at its lower end a collar 52, provided with an outstanding finger 53 and a depending lug 54. Journaled in the collar is the upstanding terminal of an axle 55, having a rearwardly extending portion 56, provided at its rear end with an outwardly extending spindle 57, on which is journaled a furrow wheel 58. A coiled spring 59, connecting the finger 53 and the rearwardly extending portion 56 of the axle, serves to hold said axle against the lug 54, and consequently yieldingly maintains the furrow wheel in parallel relation to the line of draft, all of which will be clear by reference to Fig. 3. The vertical movement of the arm 47 and consequently of the draft appliance upon the standard 51 is secured by means of a lever 60, pivoted at one end, as shown at 61, to the forwardly projecting ear 50 of the arm, said lever being connected by a link 62 with the upper end of the standard. A quadrant rack 63, located at the rear side of the guideway or boxing 49, is arranged to be engaged by a dog 64, mounted on the lever. It will be seen that by raising and lowering the lever, the guideway or boxing will be elevated or depressed, and thereby the draft appliance and front end of the plow can be correspondingly moved.

A rear furrow wheel 65 is also provided which is connected to the last disk carrier. As shown in Fig. 1 and 2, this carrier consists merely of an upstanding spindle 66 that is journaled in the rearmost beam boxing 16, and a spindle boxing 67 that receives the spindle of the rearmost disk, the spindle 66, however, being provided with a rearwardly extending lug 68. Bolted or otherwise rigidly secured to the lug 68 is an arm 69 terminating at its rear end in an upright sleeve 70, having depending lugs 71. The upright end of an axle 72 is journaled in the sleeve 70 and has an offset spindle 73 at its lower end, that has a portion located between the lugs 71 and also has the wheel 65 journaled thereon. Each of the plowing disks with the exception of the last, is, furthermore, provided with a ground wheel support. To this end, each of the disk carriers 18 has on the side of the beam opposite the disk an upstanding guide boxing 74, that is slidably mounted on an upright standard 75, the standard terminating at its lower end in a collar 76. An axle has an upstanding portion 78, journaled in the collar, a forwardly extending portion 79 that extends between the lugs 77 and 77^a, and an offset terminal 80, constituting a spindle on which is journaled a land side wheel 81. When the axle 79 is bearing against the lug 77, the wheel is disposed parallel to the line of draft or, in other words, is as illustrated in Fig. 1. Means are employed for moving the plow beams, carriers and disks upon their various standards. For this purpose bell 130

crank levers 82 are pivoted at their elbows to lugs 83, carried by the portions 27 of the disk carriers. The lower arms 84 of the bell cranks are connected by links 85 with the upper ends of the standards 75. The upper arms 86 of the bell cranks are pivoted to a common link 87, extending above the beams and having a connection 88 at its rear end with an actuating lever 89. This lever is fulcrumed upon the next to the last disk carrier and has movably mounted thereon a suitable dog 90, co-operating with a quadrant rack 91, also forming part of the disk carrier.

Each of the plowing disks is provided with a scraper 92, which has secured to its rear side a plate 93, containing a socket 94. One arm of a yoke 95 is adjustably received in this socket and is held in place by a set screw 96. The said yoke extends over the top of the disk and the other arm 97 is adjustably received in a socket piece 98, formed upon the cap 25 of the disk carrier. A set screw 99 passing through a socket piece, engages the arm 97. It will be apparent that, by adjusting the arm 97 in the socket piece 98 and by adjusting the scraper on the yoke, said scraper can be placed in substantially any desired position with respect to the disk with which it co-operates.

It will be evident that with this structure, when the draft appliance has been elevated on the front furrow wheel and the various plowing devices elevated on their respective land side wheels, the rearmost disk will also be raised as the rear furrow wheel will move on the same level with the land side wheel and the rearmost disk beam can swing in a vertical plane. This relation of parts is illustrated in Fig. 2 and in the condition therein disclosed the plow can be readily transported from place to place. To move the disks into operative positions, it is only necessary to lower the draft appliance and swing the lever 89 rearwardly, this movement thus swinging the various bell crank levers and allowing the beams, carriers and disks to move downwardly. The depth at which the disks operate can, of course, be regulated by the position of the said lever 89. When plowing in a straight line, the land side wheels will be disposed parallel to the line of draft or in the positions shown in Fig. 1. The axles 79 thereof will then be bearing against the lugs 77 and will be held thereagainst by the lateral pressure, due to the disks. The draft against the beams will not only be through the chain, namely, from the connection 32 with the draft appliance, but each draft link 41 will be operating on its respective beam, thereby rigidly maintaining the plowing disks in their operative positions. The draft through the links 41, moreover, will cause downward pressure upon the rear ends of the bills 39, and consequently this downward pressure will be exerted

through the beams and upon the disks, maintaining the same at the desired depth and yet permitting a yielding independently upward movement on the part of any disk, should it strike an immovable obstruction. In making a turn, if said turn is to the right, the front furrow wheel will caster, or in other words, the axle 55 will turn in the collar 52, and the arm 56 will turn against the tension of the spring 59 and away from the lug 54. This movement is due to the fact that the wheel 58 being in a furrow will not move laterally upon the preliminary lateral movement of the machine, but will turn on a vertical axis, and this axis will be the upright portion 80 of the axle. The beams and carriers will turn upon the spindles 78 of the various land side wheel axles until this relative movement is stopped by the lugs 77^a striking the said axles. The draft upon the links 41 is, however, not relieved and consequently the disks will be held to their work. As soon as the turn has been completed, the parts assume their original relation. In making a turn to the left, the draft on the links 41 is relieved 85 and the disks are permitted to turn on their upright axes, and as each disk has spaced connections through a pair of the links 41, with the draft appliance, when said appliance turns to the right, the disks are maintained 90 in their same relative positions and will take the full cut at the corners. The relation of the chain of beams and the disks to the front furrow wheel can be readily regulated by adjusting the connection 32 along the offset 100 11 of the draft bar and by adjusting the stirrup 43 along the main portion of said bar. The various disks can also be moved toward and from each other by adjusting the beams upon the different spindles so that the 105 amount of land taken in the furrows can be varied as found desirable. Moreover, any number of plows can be employed, necessitating merely the adjustment of the draft connections and of the connection between 110 the power and the draft appliance. The structure is, perhaps, particularly adapted for use with traction engines, though not necessarily limited thereto. One of the most important features of the invention is, 115 however, the provision of the pivoted connections between the various beams that permit the free vertical swinging movements thereof, and also the provision of the land side wheels for the different disks. By this arrangement, not only is a flexible chain provided, which will conform to the unevenness of the ground, but the structure can be made very much lighter, each beam being supported by its own wheel, and therefore, no 120 matter how long the chain is made, no additional weight is brought upon said chain or upon the furrow wheels. Consequently, the parts may be made much lighter in weight 125 without in any manner decreasing their effi 130

ciency. Furthermore, by having these different wheels journaled, as above described, a very short turn can be made, and, as soon as the turn is completed, the parts return to their operative positions. The scraper employed is also efficient, for, by having one arm adjustable in the socket of the supporting piece and by having the scraper adjustable upon the other arm, the proper position 5 of said scraper with respect to the disk can be accurately and conveniently obtained.

While the bar 9 is shown as supported at one end only, any means can be employed for supporting the other end, as for instance, 15 through the connection between the bar and the traction engine.

From the foregoing it is thought that the construction, operation, and many advantages of the herein described invention will 20 be apparent to those skilled in the art, without further description, and it will be understood that various changes in the size, shape, proportion, and minor details of construction may be resorted to without departing 25 from the spirit or sacrificing any of the advantages of the invention.

Having thus described my invention what I claim as new and desire to secure by Letters Patent, is:

30. 1. In a gang plow, the combination with a chain of beams, of connections between the adjacent beams for permitting their relative movements, said connections being independent one of the other, a plowing device connected to each beam, and a supporting wheel connected to each beam and associated with each plowing device, said wheel supporting its particular beam and plowing device and permitting the relative movements 35 of the different beams.

2. In a gang plow, the combination with a chain of connected beams, of a land side wheel located at each connection between the adjacent beams and constituting a support 45 for the adjacent ends of both beams, and plowing devices associated with the different wheels.

3. In a gang plow, the combination with a chain of flexibly connected beams, of a land 50 side wheel located at each connection between adjacent beams and constituting a support for the adjacent ends of both beams, and a plowing device located at each connection and associated with the land side wheel thereat.

4. In a gang plow, the combination with a plurality of beams, of plowing devices mounted on the beams, a plurality of land side wheels, each of which co-operates with one 60 of the beams and with a plowing device and located adjacent to the point of connection between the beams, and independent connections between the adjacent beams, each connection engaging the front end of one 65 beam and the rear end of another.

5. In a gang plow, the combination with a plurality of beams arranged with the rear end of one adjacent to the front end of the other, of a plurality of independent flexible connections between the front and rear ends 70 of adjacent beams, a plowing device mounted on each connection and a land side wheel carrying each beam and co-operating with the plowing device mounted on said beam.

6. In a gang plow, the combination with a 75 frame, of a plurality of plowing devices mounted thereon, a plurality of ground wheels, each co-operating with one of the plowing devices, devices for elevating and lowering the plowing devices upon the various ground wheels, and a common actuating device for operating the elevating and lowering devices.

7. In a gang plow, the combination with a frame, of a plurality of plowing devices 85 mounted thereon, ground wheels co-operating with the different devices, and common means for elevating and lowering the plowing devices upon the various ground wheels.

8. In a gang plow, the combination with a 90 frame including a plurality of sections, of connections between the sections, a plowing device carried by each section, a separate land side wheel supporting each section, and means mounted on said connections for elevating and lowering the plowing devices 95 with respect to the various wheels.

9. In a gang plow, the combination with a plurality of beams, of means connecting one beam to the other, a plowing device mounted on each beam, a separate land side wheel carrying each beam, and co-operating with the plowing device mounted on said beam, and means mounted on the connecting means for elevating and lowering the beams and the 105 plowing devices with respect to the various wheels.

10. In a gang plow, the combination with a plurality of standards, of ground wheels supporting the standards, a frame including a plurality of sections, each being slidable upon a standard, a plowing device carried by each section, and common means for simultaneously sliding the sections upon the standards.

11. In a gang plow, the combination with a 115 plurality of standards, of ground wheels supporting the standards, a frame including a plurality of sections, each being slidable upon a standard, a plowing device carried by each section, and a raising and lowering 120 device connected to the several standards and each section.

12. In a gang plow, the combination with a plurality of standards, of ground wheels supporting the standards, a frame including a plurality of sections, each being movable upon a standard, a plowing device carried by each section, an actuating lever, and a link connected to the lever and to the various 125 standards and sections. 130

13. In a gang plow, the combination with a plurality of standards, of ground wheels supporting the standards, a frame including a plurality of supporting sections, each being movably associated with a standard, a plowing device carried by each supporting section, a link, and a bell crank connected to each of the standards and associated sections and being also connected to the link. 5
14. In a gang plow, the combination with a plurality of pivotally connected beams, of plowing devices carried thereby, a plurality of ground wheels and standards, each beam having a sliding connection with one of the standards, an actuating lever, a link connected to the lever, and a bell crank connected to each standard and to the beam associated therewith. 10
15. In a gang plow, the combination with a plurality of standards having offset axles at their lower ends, of ground wheels journaled on the axles, a plurality of pivotally connected beams slidably mounted on the standards, connections between the beams and standards for elevating and lowering the former, and common actuating means for said connections. 15
16. In a gang plow, the combination with a plurality of pivotally connected beams, of plowing devices carried thereby, guideways carried by the beams, standards on which said guideways slide, bell crank levers having link connections with the standards and pivoted upon the beams, a link connected to the various levers, and an actuating lever pivoted to the link. 20
17. In a gang plow, the combination with a draft appliance, of a plurality of draft connections attached thereto, a plurality of plowing devices attached to the draft connections, and independent connections between the plowing devices, said latter connections also constituting means for securing the draft connections to the plowing devices. 25
18. In a gang plow, the combination with a draft appliance, of a plurality of beams, a plurality of draft devices between the appliance and beams, a plurality of independent devices directly connecting adjacent beams said devices also constituting means for connecting the draft devices to the beams, and plows carried by the beams. 30
19. In a gang plow, the combination with a draft appliance, of a plurality of beams, a plurality of draft links connected to the draft appliance and associated with the front ends of the beams, said beams being disposed with the front end of one alongside the rear end of the beam adjacent, independent connections between said adjacent front and rear ends and a plowing attachment supporting each connection. 35
20. In a gang plow, the combination with a draft appliance, of a plurality of beams, a plurality of draft links between the appliance and the beams, connections between the beams engaging the same and also engaging the links to connect the links to said beams, and plowing devices carried by the beams. 40
21. In a gang plow, the combination with a draft appliance, of a series of beams, the front portion of one being associated with the rear portion of the next adjacent, a plurality of independent connections between said adjacent portions of the various beams, a plowing attachment supported by each connection, and a draft connection between the front end of each beam and the draft appliance. 45
22. In a gang plow, the combination with a draft appliance, of a series of beams, the front end of one being connected to the rear end of the next adjacent, a plowing attachment support and a supporting wheel attached to each connection, the foremost beam having a connection with the draft appliance, and a series of links connected to the front ends of the other beams and to the draft appliance. 50
23. In a gang plow, the combination with a plurality of beams, of separate pivotal connections between adjacent beams, plow disks mounted on the beams, and a land side wheel co-operating with each disk. 55
24. In a gang plow, the combination with a plurality of beams, of devices connecting adjacent beams, draft links connected to the devices, a draft appliance connected to the links, plowing devices mounted on the connecting devices, and ground wheels associated with the plowing devices and also mounted on the connecting devices. 60
25. In a gang plow, the combination with a plurality of connected beams, of a plowing disk carried by each beam and having its axis disposed on one side of the same, and a land side wheel connected to each beam and located on the opposite side thereof to the axis of the disk, and means for raising and lowering the beams upon their respective wheels. 65
26. In a gang plow, the combination with a plurality of beams, of a device connecting the beams, a plow mounted on the device, and a supporting wheel connected to said device. 70
27. In a gang plow, the combination with a plurality of beams, of a structure connecting the beams, said structure being carried by and movable independently of one of the same, a plowing device mounted on the structure, a ground wheel mounted on the structure, and means for elevating and lowering said structure and plow on the wheel. 75
28. In a gang plow, the combination with a beam, of a plow carrier connected thereto and having a horizontal pintle, a plow mounted on the carrier, another beam mounted on the pintle and adjustable longitudinally along the same, and another plow connected to the latter beam. 80

29. In a plow, the combination with a mounting, of a beam movably connected to the mounting, a pressure device movably carried on the mounting and acting on the beam to exert a downward pressure thereon, and draft mechanism connected to the pressure device.
30. In a plow, the combination with a mounting, of a beam pivotally connected to the mounting, a pressure device pivotally connected to the mounting and acting on the beam to exert a downward pressure thereon, and draft mechanism connected to the pressure device.
31. In a plow, the combination with a beam, of a plowing device connected thereto, a pressure member having a bearing on the beam, a mounting on which the pressure device is carried, said beam being movable with respect to said mounting and a draft device having a connection with the pressure member and causing the same to exert a downward pressure on the beam.
32. In a plow, the combination with a mounting of a beam having an upright swinging movement with respect to the mounting, a plowing device carried by the beam, and means bearing against the beam for exerting a downward pressure thereupon, said means including draft mechanism connected to the beam, and a bearing device movably supported on the mounting and also engaged with the beam.
33. In a plow, the combination with a mounting of a beam having an upright swinging movement with respect to the mounting, a plowing device carried by the beam, and draft mechanism bearing upon the beam for exerting a downward pressure thereupon.
34. In a plow, the combination with a pintle, of a swinging beam connected thereto at its front end, a pressure member bearing upon the beam in rear of its connection with the pintle, and a draft device for moving the plow connected to the pressure member.
35. In a gang plow, the combination with a pivot support, of a beam pivoted thereon, a plowing device connected to the beam, a pressure member also pivoted on the support and having a bearing on said beam to exert a downward pressure thereon, and a draft mechanism connected to the pressure member for moving the plow and exerting a downward pressure on the beam.
36. In a plow, the combination with a beam having an upright swinging movement, of a plowing device carried thereby, and a swinging pressure member bearing upon the beam, said member and beam having substantially coincident journal axes.
37. In a plow, the combination with a pintle, of a swinging beam connected at its front end thereto, a swinging pressure device mounted on the pintle, and bearing upon the beam in rear of its connection with said pintle, and a draft device connected to the pressure member.
38. In a plow, the combination with a beam, of an offset pintle carried thereby, another beam journaled on the pintle, a pressure member bearing on the latter beam, and a draft device connected to the pressure member.
39. In a plow, the combination with a beam, of an offset pintle carried thereby, another beam journaled on the pintle, and a pressure member journaled on the pintle and bearing on the latter beam.
40. In a gang plow, the combination with pivotally connected beams, of draft devices, and means actuated by the draft devices for exerting downward pressure on the beams.
41. In a gang plow, the combination with a plurality of pivotally connected plowing devices, of a plurality of pivotally mounted pressure members acting on the plowing devices to exert downward pressure thereupon, and draft means connected to the pressure member.
42. In a gang plow, the combination with a plurality of pivotally connected beams and plowing devices, each having an outstanding pintle upon which another is journaled, of a plurality of pressure members journaled on the pintles and bearing on the beams, and draft mechanism connected to the various pressure members.
43. In a gang plow, the combination with a plurality of beams, of a plowing device, and an outstanding pintle carried by each beam, said beams being journaled each on the adjacent pintle, a pressure member pivoted between its ends on each pintle and bearing at its rear end on the beam, a draft appliance, and draft links connecting the appliance and the pressure members.
44. In a plow, the combination with a plow beam, of a pressure member pivoted between its ends to the beam, the rear portion of the member bearing on the beam, and a draft device connected to the front end of the pressure member.
45. In a gang plow, the combination with a draft appliance, of a plurality of beams, a plowing disk and an outstanding pintle carried by each beam, said beams being each journaled on the pintle of the adjacent beam, a pressure member pivoted between its ends on each pintle and bearing at its rear end on the beam journaled on said pintle, and draft links connected to the pressure members and to the draft appliance.
46. In a gang plow, the combination with a beam, of a plowing device movably mounted thereon, another beam connected to the movable plowing device, and independently of the first mentioned beam, and another plowing device mounted on the latter beam.
47. In a gang plow, the combination with a beam, of a plowing device connected to the beam, another beam journaled on the plowing device, and independently of the first mentioned beam, and another plowing device mounted on the latter beam.

a beam, of a plowing device pivoted to the beam, another beam connected to the pivoted plowing device independently of the first mentioned beam, and another plowing device mounted on the latter beam.

48. In a gang plow, the combination with a beam, of a plowing device pivoted to the beam, a draft device connected to the pivoted plowing device, another beam connected to the pivoted plowing device, and another plowing device mounted on the latter beam.

49. In a gang plow, the combination with a beam, of a plowing device movably mounted thereon, another beam pivotally connected to the movable plowing device independently of the first mentioned beam, and another plowing device mounted on the latter beam.

50. In a gang plow, the combination with a beam, of a plowing device pivoted to the beam and having an outstanding pintle, another beam journaled on the pintle and having a plowing device, and a draft link connected to the pintle.

51. In a gang plow, the combination with a beam, of a disk carrier pivoted to the beam and having an outstanding pintle on one side, a disk mounted on the other side of the carrier, another beam journaled on the pintle, a disk connected to said latter beam, and a draft link connected to the pintle.

52. In a gang plow, the combination with a draft appliance, of a plurality of beams, a plurality of disk carriers, each pivoted to one beam and having an outstanding pintle to which the next adjacent beam is connected, disks mounted on the carriers, standards on which the disk carriers slide, land side wheels connected to the standards, and draft links connecting the draft appliance and the disk carriers.

53. In a gang plow, the combination with a plurality of beams, of a plow associated with each beam, and a plow carrier connecting one of the plows to its beam and connected directly to the next adjacent beam, said carrier thereby constituting a coupling between the adjacent beams.

54. In a gang plow, the combination with a plurality of beams, of a structure connecting the beams, said structure having a pivotal connection with one beam on a substantially horizontal axis, and a pivotal connection with the other beam on a substantially upright axis.

55. In a gang plow, the combination with a plurality of beams, a structure having two axles disposed at substantially right angles to one another, the forward end of one beam pivotally connected to one axle and the rear end of another beam pivotally connected to the other axle.

56. In a gang plow, the combination with a plurality of beams, of a plurality of plow

carriers movably connecting the beams, plows mounted on the carriers, a draft appliance, and a plurality of separate draft devices connected to the draft appliance and to the plow carrier.

57. In a gang plow, the combination with a plurality of beams, of a plurality of plow carriers pivoted to the different beams, a draft appliance, and a plurality of separate draft links connecting the draft appliance and the carriers.

58. In a gang plow, the combination with a plurality of beams, of a plow associated with each beam, and a plurality of corresponding plow carriers, each carrier connecting one plow to its particular beam, certain of said carriers being also connected to the next adjacent beams and thereby constituting couplings between said beams.

59. In a gang plow, the combination with a plurality of beams, of a plow associated with each beam, a plow carrier connecting one of the plows to its beam and being connected directly to the adjacent beams, thereby constituting a coupling between the beams, and a ground wheel mounted on the carrier.

60. In a gang plow, the combination with a plurality of beams, disposed with the front end of one adjacent to and at one side of the rear end of the next, of independent pivoted connections between adjacent front and rear ends of the various beams, permitting the upright swinging movement thereof, plowing devices carried by the connections, a ground wheel carried by each beam, and draft devices connected to the front ends of the beams.

61. In a gang plow, the combination with a plurality of beams pivotally connected on horizontal axes and thus capable of upright swinging movement, of plowing disks supported by the connections, a land side wheel carried by each beam, said beams being vertically adjustable with respect to the wheels, and means for effecting such adjustment.

62. In a plow, the combination with a beam, of a plowing device and carrier having an offset portion, another beam adjustably mounted on the offset portion and slideable thereon toward and from the first mentioned beam, means for holding the adjustable beam against its sliding movement and in different positions on the offset portion, and a plowing device carried by the latter beam.

63. In a plow, the combination with the beam, of a plowing device, an offset pintle carried by the beam, another beam slidably mounted on the pintle, toward and from the beam carrying it, and another plowing device carried by the latter beam.

64. In a plow, the combination with a beam, of a plowing device and an offset substantially horizontal pintle carried by the beam, another beam slidably mounted on the pintle and having an upright swinging

movement thereon, and a plowing device carried by the latter beam.

65. In a gang plow, the combination with a beam, of a plowing device and an offset pintle having a connection with the beam, another beam mounted on the pintle and slideable thereon to different positions, means also slideable on the pintle for holding the latter beam in different adjusted positions on said pintle, and another plowing device carried by the said latter beam.

66. In a plow, the combination with a beam, of a plowing device, a transversely disposed pintle carried by the beam, another beam pivotally and adjustably mounted on the pintle, a yoke collar embracing the beam and slideable on the pintle, and a set screw for holding the collar against movement.

67. In a gang plow, the combination with an upright standard, of a beam slidably associated therewith, said standard having an upright collar, an axle having an upright end journaled on the collar, an intermediate portion that extends toward the front of the beam, and an offset pintle at its front end, a land side wheel journaled on the pintle, and means for maintaining the beam at different positions on the standard.

68. In a plow, the combination with a beam, of a plowing device carried thereby, an axle located at the rear of the plowing device and having a lower end portion that extends toward the front end of the beam and is capable of a limited swinging movement toward and from the plowing device, said forwardly projecting portion having a spindle at its front end, that is disposed transversely of the line of draft and a land side wheel journaled on the spindle.

69. In a plow, the combination with a beam, of a plow carrier mounted thereon and including a collar having depending lugs, an axle having an upright portion journaled in the collar, a forwardly projecting portion located between the lugs and an offset front end constituting a spindle, and a wheel journaled on said spindle.

70. In a gang plow, the combination with a plurality of pivotally connected beams having plowing devices, of a land side wheel co-operating with each device and having a swinging movement with respect thereto on a horizontal plane.

71. In a gang plow, the combination with a plurality of pivotally connected beams having plow carriers, of axles journaled on the carriers, and land side wheels journaled on the axles.

72. In a plow, the combination with a beam, of a plow carrier pivotally mounted thereon, and means for maintaining the beam and carrier against relative movement when the beam is swung in one direction and permitting such relative movement when the beam is swung in the opposite direction.

73. In a gang plow, the combination with a draft appliance, of a chain of beams adjustably connected at its front end to the draft appliance, and a plurality of draft devices connected to the various beams and adjustably connected to the draft appliance.

74. In a gang plow, the combination with a draft bar, of a chain of beams, an adjustable connection between the front end of the chain of beams and the bar, and draft means connected to the various beams and adjustably connected to the draft bar.

75. In a gang plow, the combination with a draft bar having a rearwardly extending portion provided with an offset, of a chain of beams extending diagonally across the line of draft in rear of the draft bar, an adjustable connection between the front end of the chain and the offset of the bar, a series of draft links connected to the beams, an adjustable connection between the links and the main portion of the bar, and plowing disks connected to the various beams.

76. In a plow, the combination with a beam, of a plow carrier pivotally mounted thereon, a plowing device mounted on the carrier, a standard on which the carrier is slidably mounted, a land side wheel pivotally connected to the standard, and means for sliding the carrier on the standard.

77. In a plow, the combination with a beam, of a plow carrier pivotally mounted thereon, a plowing device mounted on the carrier, a standard on which the carrier is slidably mounted, said standard having an upright collar and depending lugs at the lower end of the collar, an axle pivoted in the collar and having an offset portion located between the lugs, a spindle carried by the offset portion, a land side wheel journaled on the spindle, and means connecting the standard and the carrier for effecting a sliding movement of the latter.

78. In a gang plow, the combination with a plow beam, of a plow carrier pivoted thereto on a substantially upright axis, a plowing device mounted on the carrier at one side of said axis, a rearwardly extending arm rigidly fixed to the carrier and disposed substantially parallel to the line of draft, and a rear furrow wheel mounted on the rear end of the arm and disposed directly alongside the same.

79. In a gang plow, the combination with a plow beam, of a plow carrier pivoted thereon on a substantially upright axis, a plow disk journaled on the carrier at one side of its axis, a rearwardly extending arm rigidly fixed to the carrier below its pivotal connection with the beam, and a rear furrow wheel having a pivotal connection with the rear portion of the arm.

80. In a gang plow, the combination with a draft bar disposed transversely of the line of draft and having a rearwardly extending

portion, of a chain of beams and plowing devices, a swinging connection between the chain and rearwardly extending portion, draft devices connecting the chain and the bar separately from the first mentioned connection, an outstanding arm having a connection with the bar at said swinging connection, and a front furrow wheel adjustably mounted on the arm.

81. In a gang plow, the combination with a draft bar, of a swinging rearwardly extending section pivoted thereto, an arm connected to the bar, an upright standard on which said arm is slidably mounted, an axle pivoted to the standard, a wheel journaled on the axle, means for raising and lowering the arm on the standard, a chain of plowing devices connected to the rearwardly extending pivoted section, and draft links connecting the draft bar, and plowing devices.

82. In a gang plow, the combination with a draft appliance having a rearwardly extending portion, of a chain of beams and plowing devices connected to the rearwardly extending portion, an arm pivoted to the rearwardly extending portion, means for limiting the swinging movement of the arm, a standard located at the outer end of the arm and having a slidable engagement therewith, a front furrow wheel connected to the standard, and means for effecting an upright swinging movement of the arm on the standard.

83. In a gang plow, the combination with a draft appliance, of a standard on which said appliance has a vertical sliding movement, a collar carried by the standard and having an outstanding finger, an axle having an upright portion journaled in the collar and an offset portion forming a spindle, a front furrow wheel journaled on the spindle, and a spring connecting the axle and finger.

84. In a gang plow, the combination with a chain of beams, the front end of one being associated with the rear end of the next, of means connecting said adjacent ends of the beams, a plurality of plowing devices associated with the beams, and a plurality of land side wheels carried by said chain of beams and located adjacent to the point of connection between the beams.

85. In a gang plow, the combination with a chain of beams, the front end of one being associated with the rear end of the next, of means connecting the said adjacent ends of the beams, a plurality of plowing devices associated with the beams, a plurality of land side wheels carried by said chain of beams and located adjacent to the point of connection between the beams, and furrow wheels located respectively at the front and rear ends of the chain of beams.

86. In a gang plow, the combination with a chain of beams, the front end of one beam being associated with the rear end of the

next, of means connecting the said adjacent ends of the beams, plowing devices and associated land side wheels, carried by the connections between the beams, and furrow wheels located respectively at the front end 70 of the first beam and rear end of the last beam.

87. In a gang plow, the combination with a chain of beams, the front end of one beam being associated with the rear end of the next, of means connecting the said adjacent ends of the beams, a plurality of plowing devices associated with the beams, and a land side wheel located and operating in a position between the connected ends of the adjacent beams.

88. In a gang plow, the combination of a plurality of relatively movable frame members, of separate connections between the members that permit their relative movement, and plowing devices mounted on said connections.

89. In a gang plow, the combination with a plurality of relatively movable beams, of plow carriers pivotally connecting the beams, 90 and plowing disks journaled on the carriers.

90. In a gang plow, the combination with a plurality of frame members, of separate connections between the members, permitting their relative movement, plowing devices mounted on said connections and located on one side of the members, and supporting wheels for the different plowing devices located on the opposite side of the members.

91. A plow including a series of beams extending diagonally across the line of draft, said beams being disposed one in advance of another and parallel with the line of draft, connections between the respective beams, 105 and plowing devices and land wheels mounted on the connections.

92. A plow including a series of interchangeable hingedly connected beam members, the hinge connections having substantially horizontal axes, and plowing devices carried by the hinge connections.

93. A plow including a series of hingedly connected beam members, the hinge connections having substantially horizontal axes, 115 and plowing devices carried by the different hinge connections.

94. A plow including a series of hingedly connected beam members, the hinge connections having substantially horizontal axes, 120 separate land wheels for the respective members, and a furrow-opening device carried by each member.

95. A plow including a series of beam members, a furrow-opener for each beam, and 125 a series of rotary structures, each serving to connect two adjacent beam members and connect a furrow-opener to its beam.

96. A plow including a series of flexibly connected beam members having separate 130

and independent connections to permit the relative upward flexion of the beam members, land and furrow wheels supporting said series of members, and furrow openers carried by said connections.

97. A plow including a series of beam elements, and connections between said elements permitting the same to flex relatively in either a vertical or a horizontal direction, and furrow-openers supported by the connections.

98. A plow including a beam member, a rotary furrow-opener support carried thereby, a second beam member laterally movable relatively to the first named member, and means whereby such relative lateral movement of the beam members will effect the turning of the furrow-opener support to change the angular relation of the furrow-opener with respect to the beam which supports it.

99. In a gang plow, the combination with a frame comprising relatively movable connected sections, of a plowing device movably mounted on each connection, and means operated by the sections on their relative movement to effect the adjustment of the plowing device relative to the connection on which it is movably mounted.

100. In a gang plow, the combination with a beam, of a plow carrier pivotally connected thereto on a substantially upright axis, a plow mounted on the carrier, another beam pivoted to the carrier on a substantially horizontal axis and having an upright swinging movement thereon, and another plow connected to the latter beam.

101. In a gang plow, the combination with a plurality of beams, of plowing devices carried thereby, a ground wheel for each device, and means for raising and lowering all the plowing devices upon and with respect to the wheels.

102. In a gang plow, the combination with a plurality of beams, of separate devices for pivotally connecting one beam to the beam next adjacent thereto, ground wheels asso-

ciated with each beam, and means mounted on the connecting devices for effecting a relative movement between the beams and the wheels.

103. In a gang plow, the combination with a plurality of beams, of separate devices for connecting each beam to the next adjacent beam, a plowing device, and a ground wheel mounted on each connection, and means for raising and lowering the plowing devices and beams upon the wheels.

104. In a gang plow, the combination with plows, of a plurality of flexibly connected beams having plowing devices thereon, a draft appliance, a connection between the foremost beam and the draft appliance, a plurality of draft devices connected to the various beams, and a common fastener securing the draft device to the draft appliance and adjustable on the draft appliance toward and from the connection of the foremost beam therewith.

105. In a gang plow, the combination with pivotally connected beams, of plowing devices carried thereby, and pressure means for exerting downward pressure on the different beams.

106. In a gang plow, the combination with a plurality of beams, of a structure connecting the beams, said structure having a pivotal connection with each beam, said connections having axes disposed in annular planes, and a plow carried by the pivotal connection.

107. In a gang plow, the combination with a plurality of beams, of a structure connecting the beams, said structure having a pivotal connection with each beam and said connection having axes disposed in angular planes, and a plow and a ground wheel carried by the pivotal connection.

In testimony, that I claim the foregoing as my own, I have hereto affixed my signature in the presence of two witnesses.

SAMUEL V. WEEKS.
